CLAIM

The ornamental design for a fixing pad, as shown.

DESCRIPTION

FIG. 1 is a two-dimensional front view of a first variant the fixing pad, the back view thereof being identical;

FIG. 2 shows the first variant of the fixing pad of FIG. 1 at a different scale and in its environment;

FIG. 3 is a two-dimensional front view of a second variant the fixing pad, the back view thereof being identical;

FIG. 4 is a two-dimensional front view of a third variant the fixing pad, the back view thereof being identical; and,

FIG. 5 is a two-dimensional front view of a fourth variant the fixing pad, the back view thereof being identical.

The elements and structures shown in dotted lines are shown for illustration purposes only and do not form part of the design.
